UNITED STATES PATENT OFFICE.

PERCY M. HOLDSWORTH, OF ST. LOUIS, MISSOURI.

LOCOMOTIVE ENGINE AND TENDER COUPLING.

No. 887,806.

Specification of Letters Patent.

Patented May 19, 1908.

Application filed June 24, 1907. Serial No. 380,510.

To all whom it may concern:

Be it known that I, PERCY M. HOLDSWORTH, a citizen of the United States, residing at St. Louis, in the State of Missouri, have invented a new and useful Improvement in Locomotive Engine and Tender Couplers, of which the following is a specification.

My invention relates to the coupling-bar of a locomotive engine and tender, which ordinarily consists of a horizontally arranged flat bar of iron or steel coupled at its ends by pins inserted vertically therethrough, and through jaws or brackets fixed to the engine and tender frames, whereby the latter, on driving the pins home, are drawn together at their meeting ends, the said ends being usually provided with chafing-irons or their equivalents, adapted to ride against each other at all times.

My invention has for its object, to increase the coupling bearing surface of the bar, to take up the wear of same, to dispense with the ordinary pins and chafing-irons, and to enable the coupling-bar with its combined parts to be readily disconnected for uncoupling the engine and tender.

The invention consists in features of novelty as hereinafter described and claimed, reference being had to the accompanying drawing forming part of this specification, whereon,

Figure 1, is a vertical longitudinal section (partly in elevation) through my improved coupling-bar and its combined parts on line 1; 1, in Fig. 2; Fig. 2, a horizontal section (partly in top plan view) through the same on line 2, 2, in Fig. 1; Fig. 3, a vertical transverse section through the coupling-bar on line 3; 3, in Fig. 1, looking to the right, showing its combined parts in end elevation, and Fig. 4, a similar view thereof looking to the left.

Like letters and numerals of reference denote like parts in all the figures.

a represents my improved coupling-bar which is composed preferably of cast steel integral throughout and having its shank or body 1 preferably tubular in cross section.

At and around each end and adjacent portion of the shank 1 is preferably, formed a spherical projection *b*, (or other suitably shaped enlargement) which in the present case is a sphere or ball having its center along the longitudinal center line of the shank 1, and divided transversely to the latter into

two opposite spherical segmental webs or disks 2 and 3 (hereinafter referred to as spherical segments) which are united to each other on their inner concave sides by ribs 4 60 suitably spaced around and united to the shank 1 as shown. Or if desired the projection *b* may be a complete sphere or ball integral with or attached to the shank 1. Furthermore, if desired the spherical segments 65 (or other analogous enlargements) 2 and 3, in lieu of being integral with the shank 1 as described, may be separately constructed therefrom and attached thereto in any suitable manner.

To the tender frame *c*, preferably between the longitudinal channels 5, or equivalents thereof, is fixed a housing or box *d* which is preferably open at the bottom, and otherwise adapted to receive one end portion of the 75 coupling-bar *a* with its spherical segments 2 and 3, and the combined blocks *e*, *e'*, (hereinafter described), a bottom opening 6 and upper opening 6' communicating therewith being formed through the front wall 7 of the 80 housing *d* for the passage and play therethrough of the shank 1 of the bar *a* when so assembled.

Against the outer convex side of the end spherical segment 2 is fitted the block *e* before mentioned, while around the shank 1 and against the convex side of the opposite spherical segment 3 is fitted the block *e'*, which in the present case is made in halves bolted together, the bearing faces of the blocks *e*, *e'*, 90 against the spherical segments 2 and 3 being concave correspondingly thereto and their other sides preferably straight.

The end portion of the shank 1 with the spherical segments 2 and 3 and the blocks 95 *e*, *e'*, fitted thereto as described, is then inserted within the housing *d* through its bottom opening and the latter closed by a cover 8 having an upright tongue 8' for closing the opening 6 allowing passage of the shank 1 100 into the upper opening 6'. In this assembled position of the parts, the block *e* engaged on its front side by the spherical segment 2, bears at its rear side preferably, against a liner 9, (which may be either flat as 105 shown, wedge-shaped, or otherwise as found most suitable) interposed between it and the rear wall 7' of the housing *d* (or against the rear wall 7 when the liner is absent) and forms a joint or bearing surface for the 110 tender end of the coupling-bar *a* for resisting the "buffing" stress therethrough, while the

block e' , engaged on its rear side by the spherical segment 3 , bears at its front side against the front wall 7 of the housing d and forms a joint or bearing surface for the tender end of the coupling-bar a for resisting the "pulling" stress therethrough. Similarly, to the engine frame f is fixed a housing or box d' which is open at its front end for receiving the other end portion of the coupling-bar a with its corresponding spherical segments 2 and 3 and blocks g and g' , which are similar to and operate in the same manner as the blocks e, e' , except that the pulling block g' is inclosed by a socket-case h made in halves bolted together by bolts 10 and rigidly secured to the housing d' by keys 11 , or otherwise, the socket-case h having an opening 12 outward therefrom for the passage and play of the shank 1 of the bar a .

It will be noted that the opening 6 through the front wall 7 of the tender housing d , and the opening 12 from the socket-case h of the engine housing d' are flared outward respectively, for allowing free play of the bar a about its spherical segments 2 and 3 in every direction.

Among the advantages of my invention are, that by substituting the spherical segments 2 and 3 , integral with (or fixed to) each end of the coupling-bar a , for the ordinary vertical pins, increased bearing surface is obtained in resisting the buffing and pulling stress on the bar, also a more rigid and at the same time adjustable connection is effected, and chafing-irons dispensed with. Furthermore, by the use of liners the wear of the bearing surfaces can be taken up, and by removing the cover 8 and the keys 11 the coupling-bar a with its combined parts can be readily removed for uncoupling the engine and tender.

What I claim as my invention and desire to secure by Letters Patent is:—

1. In a locomotive engine and tender coupler, the combination of a bar, a spherical projection around each end and adjacent portion of the bar, a housing therefor on the engine and tender frames respectively, a block adapted to bear on one side against the convex portion of the said projection and on the other side against the corresponding wall of the housing for resisting the pulling and buffing stress of the bar, and means for assembling the said projection and blocks with the said portion of the bar within the housing, and for the play of the bar through a wall of the housing, substantially as described.

2. In a locomotive engine and tender

coupler, the combination of a bar, a spherical projection around each end and adjacent portion of the bar, a housing therefor on the engine and tender frames respectively, a block adapted to bear on one side against the convex portion of the said projection, and on the other side against a suitable liner intermediate thereto and to the corresponding wall of the housing for resisting the pulling and buffing stress of the bar, and means for assembling the said projection and blocks with the said portion of the bar within the housing, and for the play of the bar through a wall of the housing, substantially as described.

3. In a locomotive engine and tender coupler, the combination of a bar, a spherical projection around each end and adjacent portion of the bar, a housing therefor on the engine and tender frames respectively, a block adapted to bear on one side against the convex portions of the said projections respectively, for resisting the pulling and buffing stress of the bar, one of the said blocks on one end portion of the bar being adapted to bear on its other side against a socket-plate removably fixed in the corresponding housing, and the other said blocks against the corresponding walls of the housings, and means for assembling the said projections and blocks with the said portions of the bar within the housings, and for the play of the bar through the front walls of the housings, substantially as described.

4. A locomotive and engine coupler, comprising a bar having enlarged end portions, a housing for the said portions on the engine and tender frames respectively, blocks adapted to bear against the said portions so as to prevent rectilinear movement, while permitting oscillation of the bar thereabout, and means for holding the blocks within the said housings, substantially as described.

5. A locomotive engine and tender coupler, comprising a bar having enlarged end portions, a suitable bearing for the said portions on the engine and tender frames respectively, the said bearings being adapted to prevent rectilinear movement, while permitting oscillation of the bar thereabout, substantially as described.

In testimony whereof I have signed my name to this specification in the presence of two subscribing witnesses.

PERCY M. HOLDSWORTH.
